UNITED STATES PATENT OFFICE.

JAMES HARTNESS, OF SPRINGFIELD, VERMONT.

METAL-TURNING TOOL.

1,130,275.

Specification of Letters Patent. **Patented Mar. 2, 1915.**

Original application filed November 17, 1908, Serial No. 463,002. Divided and this application filed July 30, 1912. Serial No. 712,265.

To all whom it may concern:

Be it known that I, JAMES HARTNESS, a citizen of the United States, and resident of Springfield, in the county of Windsor and 5 State of Vermont, have invented certain new and useful Improvements in Metal-Turning Tools, (Case B,) of which the following is a specification.

This invention has relation to metal cutting tools of the type in which the chip or cutting is removed from the work in the form of a substantially continuous band or strip, necessitating the employment of means for breaking the chip or cutting into relatively short length.

Referring to the drawings,—Figure 1 represents in front elevation a turning tool embodying the invention. Fig. 2 represents a vertical section through the tool. Fig. 3 10 represents a horizontal section through the tool. Figs. 4 and 5 represent sections on the lines 4—4 and 5—5 respectively of Fig. 2. Fig. 5^a represents a cross section through the cutter holder to illustrate the means for limiting the oscillation of the cutter bar. Fig. 25 6 illustrates a portion of the cutter carrier and the chip breakers, the cutter bar being broken off. Fig. 7 illustrates the same parts looking from the other side. Fig. 8 represents an end view of the cutter carrier detached, with the various parts thereon. Figs. 9 and 10 are sectional views illustrating the operation of the deflectors or chip breakers. Figs. 11 to 15 inclusive illustrate 30 another form of chip breaker or deflector which may be employed in connection with the tool, Fig. 14 representing a section on the line 14—14 of Fig. 13, and Fig. 15 representing a section on the line 15—15 of Fig. 40 11. Figs. 16, 17 and 18 show the shoe having the chip deflector formed at the end thereof.

The tool as a whole is illustrated and described in my co-pending application Serial 45 No. 463,002, filed November 17, 1908, of which this is a division. The main features of the tool may be briefly described as follows: The body 25 consists of a standard having a base 27 adapted to be secured by 50 any suitable means to the tool slide of a lathe, the standard being provided with an aperture through which the work may pass. A rest holder 26, substantially C-shaped in form, is attached to the standard, being provided with apertures 28 to receive dowels 29.

The holder serves as a support or carrier for work rests 30, and to it is pivoted the cutter carrier 48 to be hereinafter described in detail. Each work rest consists of a rotatable disk or member having an eccentric shank 60 journaled in a sleeve or bushing 32 arranged in a cylindrical aperture 23 in the holder 26. The ends of the shanks 31 rest against pins 32 which in turn bear against transverse pins 35 passed through the projecting ends 65 of the sleeve 32. The said pins 35 have knobs 36 and constitute handles for rotating or oscillating the sleeves. Each sleeve has a rib 37 adapted to be passed through a slot 33 into an enlargement 38 of its receiving 70 socket 33, and forms a stop member which may be registered with and engage the end of any one of a series of abutment screws 40. The cut-away portion 42 of each of the handle pins will engage the head of the screw 75 40 when the end of the latter is engaged by the rib or slot member 37, so that the sleeve 32 will be held against accidental dislocation. The screws 40 are set in different positions to provide a rapid adjustment of 80 each of the work rests.

A lubricant is supplied to the work rests through a duct 43 and ducts 44. The abutment screws may be locked in place by pins 45 engaged by a beveled bar 46, the latter 85 being apertured to receive loosely a screw 47 projecting from the holder 26.

The cutter carrier is indicated at 48. It consists of a block having at its inner end a partially cylindrical ear 49 located in a complementary socket 50 on the body portion 26. The ear 49 projects into and lies between two ears 51, 51 formed on the rest holder or carrier 26.

52 indicates a pivot pin by which the cutter carrier is pivoted to the rest carrier. This pin is of sufficient length so that its extremity 53 which projects entirely through the rest carrier 26, enters an aperture 54 in the body 25 where it is clamped by a screw 100 154.

The shape of the cutter carrier will be seen from an inspection of Figs. 1, 4 and 5. It has in its front face a recess to receive the cutter bar and its shoe as will be explained. The cutter bar is indicated as a whole at 57. It consists of an elongated bar having at one end a longitudinal cutting edge formed by two faces which are preferably at an acute angle as illustrated in Fig. 8. The inner 115

face of the cutting edge is adapted to rest flat against the work, whereas the other face or top slope is at a wedging angle so as to wedge the chip away from the face of the work. The inner face of the cutter which rests against the work, is substantially a continuation of one side face of the cutter shank so that the cutting edge forms substantially a continuation of the corner of the shank. The under side or bottom of the cutter is cylindrically curved about the corner line as an axis. Rearward from the cutting edge, the outer side of the shank of the cutter has a rib 58 which is utilized in holding the cutter in place. The carrier 48 has in one of its side faces, as previously stated, a recess in which the cutter is located as shown in Figs. 4 and 5. The upper wall 59 of the recess has a downwardly projecting lip 60 against which the flat inner face of the shank may rest. The cutter itself is seated upon a rest or shoe which is indicated at 61. The under part of this shoe is cylindrically convex and is placed upon a concave seat 62 in the cutter carrier. The upper surface of the shoe 61 is concave so as to receive the convex under side of the cutter 57 and permit the oscillation of the cutter which is a feature of the tool described in my prior application Serial No. 406,588, filed December 16, 1907. The cutter carrier is provided with upwardly projecting lips 63 to prevent any lateral movement of the shoe and the shoe has similar lips 64 to limit the lateral movement of the cutter bar in one direction. At this end, the shoe 61 has an upwardly projecting lip 65 against which the end of the cutting nose of the cutter may seat itself. In addition to forming a seat for the cutter, the shoe also serves to support one of the chip deflectors or breakers as will be subsequently explained.

In order that the cutter and its shoe may be properly clamped in the cutter carrier, I provide any convenient clamping mechanism such, for example, as those shown in Figs. 4 and 5. 66 and 67 represent two clamping members which are semi-cylindrical and which are located in semi-cylindrical sockets in the cutter carrier. The flat faces of these two clamping members engage the rib 58 on the cutter bar so that by rotating said members, they force the cutter bar against the lips 60 and also force the cutter bar and its shoe against the seat 62 on the cutter carrier. For rotating said clamping members, I provide pins 68, 69, respectively, which are moved longitudinally by screws 70, 71. The end of the pin 68 is flat and it engages an edge on one side of the axis of the member 66, so that, when the pin 68 is forced upwardly, it will effect the rotation of the said member. The pin 69, however, is provided at its end with a transverse con-

will engage the convex side of the member 67. In either case, the clamp is partially rotated and is forced against the rib 58 so as to press the cutter against the lip 60 and also downwardly against its shoe. By loosening the screws 70, 71, the cutter bar and its shoe may be adjusted longitudinally. The clamping member 67 projects beyond the end of the cutter carrier, and is provided with a rib 72 which may be engaged with any one of a series of transverse notches 73, 73 in the cutter bar so as to establish a practically rigid engagement of the cutter bar with the clamping member 67. The clamping member itself may be adjusted longitudinally relatively to the pin 69. For the purpose of further limiting the lateral oscillation of the cutter bar, I place on the side of it opposite the lips 64, a pin 74 which will engage the lower portion of the inner side of the cutter bar (see Fig. 3). This pin is beveled at its end so that it may be engaged by a wedge-shaped pin 75, the latter being adjusted by a screw 76. By means of the screw 76 and the pins 74, 75, the cutter, if desired, may be clamped against any lateral movement, or they may be adjusted to permit the cutter to oscillate slightly so that the inner face of its cutting edge may follow the face of the work.

The cutter carrier has pivoted to it a yoke 77 having side bars 78 which straddle the cutter carrier, the side bars being pivoted thereto by pivot pins 79 having an eccentric sleeve 80 rigidly connected therewith. A handle 81 is secured to the pivot pin whereby it may be rocked to adjust the cutter carrier with reference to the yoke and to the work. Either of two abutment screws 82 and 83 may be engaged with a hardened socket piece 84 in an arm on the body 26 to locate the cutter with reference to the work. The said screw may be secured after adjustment by any suitable means.

The chips, which are removed from the work by the cutter, are tough and strong, so that it becomes necessary, as previously explained, to deflect them in the proper direction and also in many cases to break them. As illustrated upon the drawings, the chip deflectors now to be described are so arranged and related as to effect the breaking of the chips in relatively short lengths.

Referring to Figs. 6 to 10 inclusive, it will be observed that two deflecting members are employed, indicated respectively at 90 and 91. The member 90 is formed on the shoe 61 and it projects laterally across the inner end of the cutter carrier. Its upper surface is recessed as at 92 so as to form a curved deflecting surface 93 which is in proximity to the top slope or outer face of the cutter as shown in Fig. 9. This curved surface 93, as best shown in the two sectional views in Figs. 9 and 10, is of such

character that the chip is guided into an unnatural path both axially of the work and also laterally away from the work. The recess 92, formed by the curved surface 93, 5 serves as a chute which is open at one end for the discharge of the broken chips. Immediately above the deflecting member 90 is the member 91 which consists of a block held in place by a lip 94 on the cutter carrier and by a pin 95. The under side of the member 91 is recessed to form a curved surface 96 which opposes the curved surface 93, and which assists in guiding the chip outwardly from the work and which causes 10 the chip to be bent about the deflecting surface 93 so as to break it as the chip travels from the face of the work. In this example, the chip is guided entirely through the tool body and is discharged in front of the tool 15 (considering the position of the tool when it is operating upon the work).

In Figs. 11 to 18 inclusive, I have shown the chip breakers or deflectors which are arranged so that the chips are deflected 20 downwardly through the cutter carrier so as to be discharged therebelow. In this case, the cutter shoe is provided with the lateral extension 98 which constitutes one deflecting member, this extension lying across and being supported upon the lower portion of the cutter carrier 48. The member 98 lies in front of the end of the upper portion of the cutter carrier so as to leave a space between them, this space being indicated at 25 99 in Fig. 14. The configuration of the member 98 is apparent in Figs. 13 to 18 inclusive. It has the curved deflecting surface 100 by which the chip is guided away from the face of the work and slightly outward 30 from the work. In conjunction with the deflecting member 98, I employ a second deflecting member 101 which is bifurcated so as to straddle a pin 102 projecting from the end of the cutter carrier. In this case, for 35 the adjustment of the deflector, I employ a rock shaft 103 having an eccentric pin 104 at its end which extends into an aperture in the member 101. The face of the member 101, which confronts the member 98, is concaved, being curved downwardly so that, 40 when it is engaged by the chip, the chip is bent about the deflecting surface 100 of the member 98 and is caused to break and be discharged downwardly through an aperture 105 in the cutter carrier 48. In both of 45 these constructions, which have been described, the deflectors are located so that the chip, on leaving the top slope of the cutter, is bent laterally or flatwise (*i. e.* longitudi-

nally of the work) at a sufficiently abrupt 60 angle so that, when it engages the second deflector, it is broken into relatively short lengths, such fracture not taking place at the point of cleavage of the chip from the face of the work but below the top slope of 65 the cutter.

This application is a division of my application filed November 17, 1908, pursuant to which Letters Patent No. 1,054,840 were granted March 4, 1913. I do not herein 70 claim the work rests and means for adjusting and positioning the cutter and the work rests, claimed in my copending application Serial No. 712,264, which is likewise a division of my first-mentioned application. 75

Having thus explained the nature of my said invention and described a way of making and using the same, although without attempting to set forth all of the forms in which it may be made or all of the modes of 80 its use, what I claim is:—

1. In a metal-turning tool, a cutter holder, a cutter thereon having an inner face and a top slope, and a shoe for the cutter having a chip-deflecting surface located adjacent 85 the top slope adapted to deflect the chip out of its natural path.

2. In a metal-turning tool, a cutter holder, a cutter thereon having an inner face and a top slope, a shoe for the cutter having a 90 chip-deflecting surface located adjacent the top slope adapted to deflect the chip out of its natural path, and means coöperating with said surface to automatically bend and break said chip into sections. 95

3. In a metal-turning tool, a cutter holder, a cutter thereon, comprising a bar having a cutting edge, a shoe on the holder having a chip deflecting portion located at the side of said cutting edge, and extending laterally 100 therefrom, and a chip-breaking member located on said holder above said deflecting portion to coöperate therewith in breaking the chip into sections.

4. In a metal-turning tool, a cutter holder, 105 a cutter thereon, comprising a bar having a cutting edge, chip-breaking members located on said holder and spaced apart to provide a chip-receiving aperture, said aperture extending laterally from said cutter and having opposing walls and an open mouth for the discharge of the chip sections. 110

In testimony whereof I have affixed my signature, in presence of two witnesses.

JAMES HARTNESS.
